UNITED STATES PATENT OFFICE

119,803

DESIGN FOR A TEXTILE FABRIC

Curt E. Forstmann, Montclair, N. J.

Application April 7, 1939, Serial No. 84,123

Term of patent 14 years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

The sole figure is a plan view of a piece of fabric showing the design.

The design is a series of warp-wise stripes having a knitted appearance and showing an alternate dull and lustrous effect resulting from a contrasting arrangement of the twists of the yarn.

I claim:

The ornamental design for a textile fabric, as shown and described.

CURT E. FORSTMANN.
